ELECTRIC SQUIB FIRING DEVICE

Filed April 23, 1946

UNITED STATES PATENT OFFICE

2,506,592

ELECTRIC SQUIB FIRING DEVICE

William M. Harton, Conway, Ark.

Application April 23, 1946, Serial No. 664,182

1 Claim. (Cl. 175—115)

(Granted under the act of March 3, 1883, as amended April 30, 1928; 370 O. G. 757)

1

The invention described herein may be manufactured and used by or for the Government for governmental purposes, without the payment to me of any royalty thereon.

The present invention relates to a firing device and, more particularly, to an apparatus for firing multiple electric squibs. The device of the present invention has particular utility in connection with the electrical firing of rockets from multiple rocket launchers.

It is an object of the present invention to provide a reliable device for firing multiple electric squibs which will combine the functions of operating a selector switch to electrically connect the desired squib or squibs in an open circuit with a source of electrical energy and closing the electrical circuit to fire the squib or squibs.

A further object of the invention is to accomplish the functions set forth above in sequence so that the squib or squibs which it is desired to fire are selected before the firing action takes place.

Another object of the invention is to accomplish the above-named objects with a device which may be used at the same time to operate a generator for providing the electrical energy required to fire the squibs.

A particular object of the invention is to provide a device having the utility and novelty discussed above which may be operated by a lanyard.

Another object of the invention is to provide a device for accomplishing the above-named objects which is self-contained and sufficiently compact for mounting on the gun, launcher, or vehicle with which it is to be used.

The accomplishment of the above and other objects will be apparent from the following description of a specific embodiment of the invention shown in the drawings in which

Figure 1 is a plan view of the assembled device.

Figure 2 is a sectional view taken on line 2—2 of Fig. 1.

Figure 3 is a cross-sectional view of the safety switch taken along the line 3—3 of Figure 1 and looking in the direction of the arrows.

Referring to the drawings, the apparatus is mounted on a base plate 1 adapted to be secured to a gun, launcher, vehicle or the like. Near one edge of the plate, there is disposed an operating bar 2 which is slidably mounted on the plate by studs 3 and elongated apertures 4 to permit limited longitudinal movement of the bar with respect to the plate 1.

2

One end of the bar 2 is pivotably connected to a lever arm 5 which is pivotally mounted on the plate by pivot bolt 6. A second lever arm 7 which is pivotally mounted on plate 1 at the pivot bolt 5 is connected at one end by the pin 9 moving in slot 9' to the end of lever arm 5. The opposite end of lever arm 7 is pivotably connected to a toggle 10 to which may be attached a lanyard 11. It will be apparent from the foregoing disclosure that a pull on the lanyard 11 operating through the interconnected pivoted lever arms 5 and 7 will cause the bar 2 to be moved longitudinally on the studs 3 to the limits of the apertures 4. A pin 25 also is provided to limit pivoting movement of the lever arm 7. When the pull on the lanyard 11 is discontinued, a spring 12 attached at one end to the base plate 1 and at the other end to lever arm 5 adjacent the pin 9 returns the device to its original position.

20 The opposite end of bar 2 is pivotably attached to a lever arm 13 which is pivotably mounted by pivot bolt 14 on the base plate 1. The free end of lever arm 13 is connected to a toggle 15 to which may be attached a lanyard 16 for optional use. Pin 26 is provided to limit pivoting movement of lever arm 13.

A pivotably mounted pin 17 is provided on the end of lever arm 13 adjacent the toggle 15 having an aperture 18 to receive the end of rod 19 which is threaded to hold adjusting nuts 20 for adjustably securing the rod 19 to pin 17. The opposite end of rod 19 is formed with a collar 21 for retaining spring 22 on the rod 19. A sleeve member 23 is slidably mounted on rod 19 in contact with spring 22. The sleeve member 23 is pivotably mounted on the arm 24 which is pivoted on the center bolt 27 of a selector switch.

40 A spring loaded pawl 29 is mounted on the arm 24 to engage a metal ratchet wheel 30 rotatably mounted on the center bolt 27, but electrically insulated therefrom by insulating bushing 31. The ratchet wheel 30 carries an electrical contactor 32 for successively contacting the metal plates 33 radially mounted on an insulator base 36. Each of the plates 33 is provided with a connecting post 34 adapted to be connected to a lead wire from one or more electric squibs not shown in the drawing.

45 The ratchet wheel 30 makes electrical contact through a plurality of nibs 35 with a metal ring 36 which is insulated by bushing 37 and separator 38. Spring 43 retained on the bolt 27 by nut 44 urges the wheel 30 downwardly to establish good electrical contact of the nibs 35 with the ring 36. 55 An arm 39 on the ring 36 is provided with a con-

necting post 40 to receive a lead wire 41 to be described more particularly hereinafter.

In view of the above description, it will be seen that a pull on either lanyard will cause lever arm 13 to pivot at 14 thus moving rod 19 longitudinally causing ratchet arm 24 and thus the ratchet wheel 30 to rotate in a clock-wise direction. A stop 42 is provided to limit movement of the arm 24 and thus the wheel 30 to a distance just sufficient to move the contactor 32 to the next metal plate 33, thus establishing an electrical circuit between said next metal plate and the arm 39.

When further movement of the arm 24 is prevented by stop 42, further pivoting of the lever arm 13 and longitudinal movement of rod 19 is permitted by the compression of spring 22.

The device is provided with a source of electrical power which, in the preferred embodiment, is a conventional 10-cap blasting machine 45 which contains a generator operated by a crank arm 46. Attached to the crank arm 46 is a connecting link 47 which is journaled on the bar 2 at the journal 48. By reason of this mechanical linkage, longitudinal movement of the bar 2 energizes the blasting machine.

One connecting post 49 of the blasting machine 45 is connected to the lead wire 41 which, as described above, is attached to the connecting post 40 of arm 39 of the selector switch. The other connecting post 50 of the blasting machine 45 is connected by wire 60 to arm 51 of the simple safety switch 52. Arm 53 of the switch is connected by wire 54 with a connecting post 55 adapted to receive a lead line from the squibs to be fired. A wedge member 56 is mounted on the bar 2 and adapted to be moved into and out of engagement with arms 51 and 53 to close or open the circuit upon longitudinal movement of bar 2. The wedge member 56 is so situated on bar 2 that the circuit is not closed until after the arm 24 of the selector switch has reached the stop 42. Thus it will be seen that a pull on the lanyard will index the selector switch to a new position before the safety switch is closed thereby insuring contact with the next metal plate 33 on the selector switch before a squib connected therewith is fired.

If desired a stand-by battery 57 as shown in dotted lines in Figure 1 may be provided for use in case of malfunction of the blasting machine 45. Battery 57 may be electrically connected to the arm 51 of switch 52 and with connecting post 40 of the selector switch by wires 64 and 65, respectively, shown in dotted lines.

It will be apparent from the above description that electric squibs connected to the metal plates 33 and connecting post 55 can be rapidly and conveniently fired consecutively by successive pulls on one of the lanyards.

The specific embodiment of the invention described above will be subject to variation by one skilled in the art within the scope of the invention, and all such variations are intended to be included within the scope of the following claim.

I claim:

A firing device for firing a plurality of electric squibs in sequence comprising a selector switch having a plurality of radially disposed contact plates adapted to be electrically connected to a plurality of electric squibs, a rotatable ratchet wheel on said switch having a contactor for making electrical contact with one of said plates selectively, a ratchet arm for rotating said ratchet wheel, a stop for limiting movement of the ratchet arm to a distance sufficient to move said contactor to the next contact plate, a lanyard, a bar actuated by said lanyard mounted for limited longitudinal movement, a safety switch electrically connected to said contactor constructed and arranged to be closed by longitudinal movement of said bar a predetermined distance, a generator for generating electrical energy electrically connected to the switch and adapted to be electrically connected to a plurality of electric squibs, said generator being actuated by longitudinal movement of said bar, a mechanical linkage between said bar and said ratchet arm for moving said arm the distance permitted by said stop prior to the closing of the safety switch, said linkage including a spring member arranged to transmit force between said bar and said ratchet arm without limiting continued movement of the bar, and a second spring member for returning the bar to its original position.

WILLIAM M. HARTON.
